US00D988353S

(12) **United States Design Patent** (10) **Patent No.:** **US D988,353 S**
Kennedy et al. (45) **Date of Patent:** **** Jun. 6, 2023**

(54) **DISPLAY SCREEN OR PORTION THEREOF WITH GRAPHICAL USER INTERFACE**

(71) Applicant: **Stryker Corporation**, Kalamazoo, MI (US)

(72) Inventors: **Jeffrey Alan Kennedy**, Kalamazoo, MI (US); **Kurosh Nahavandi**, Portage, MI (US); **Benjamin John Purrenhaege**, Kalamazoo, MI (US); **Donald Scott Herzog**, Kalamazoo, MI (US); **Ian Christopher Geiman**, South Lyon, MI (US)

(73) Assignee: **Stryker Corporation**, Kalamazoo, MI (US)

(**) Term: **15 Years**

(21) Appl. No.: **29/805,157**

(22) Filed: **Aug. 25, 2021**
Related U.S. Application Data

(63) Continuation of application No. 29/696,048, filed on Jun. 25, 2019, now Pat. No. Des. 931,299.

CLAIM

We claim the ornamental design for a display screen or portion thereof with graphical user interface, as shown and described.

DESCRIPTION

The FIGURE is a front view of a display screen or portion thereof with graphical user interface showing our new design.

The broken lines in the FIGURE show a display screen or portion thereof and form no part of the claimed design.
